UNITED STATES PATENT OFFICE.

JOHN C. COLLETT, OF DAYTON, OHIO.

CARBURETER.

1,183,538.

Specification of Letters Patent. Patented May 16, 1916.

Application filed February 2, 1914. Serial No. 815,804.

To all whom it may concern:

Be it known that I, JOHN C. COLLETT, a citizen of the United States, residing at Dayton, in the county of Montgomery and State of Ohio, have invented certain new and useful Improvements in Carbureters; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in carbureters.

The main object of my invention is to provide a carbureter which has a maximum of efficiency and is simple in construction.

With the above object in view, the invention consists in the main of an inner tubular member in which a jet-nozzle is placed and which furnishes a constant air passage to said nozzle; a chamber surrounding said tubular member from which a variable supply of air is furnished to the space above said inner tube and jet nozzle, and a valve controlling the admission of air from said chamber, said last named valve surrounding the inner tubular member and constructed and arranged to actuate a needle valve which controls the jet-nozzle.

Another object of the invention is to provide means for preventing any fuel, which may become condensed in the manifold and carbureter, being deposited on the air valve and the subsequent liability to choke the carbureter when the engine is started.

Referring to the accompanying drawings, Figure 1 is a vertical sectional view of the carbureter, the same being on the line *d-d* of Fig. 2; Fig. 2 is a section on the line *a-a* of Fig. 1; Fig. 3 is a view similar to Fig. 1, showing a modified construction of the needle valve; Fig. 4 is a detail view of the air and fuel valves shown in Fig. 1 with the parts shown in a different position; Fig. 5 is an enlarged detail view of the fuel valve; Fig. 6 is a section on the line *b-b* of Fig. 1; and Fig. 7 is a section on the line *c-c* of Fig. 1.

Throughout the specification and drawings, similar reference characters indicate corresponding parts.

Referring more particularly to the draw-

ings, 1 represents a shell which, together with an inner tubular member 2, forms an oil or float-chamber 3. The top cover of said chamber consists of a cap 4 secured to the upper end of the inner tubular member 2. The lower end of said tubular member 2 is provided with a bottom 5 which is instrumental in uniting the parts 1, 2 and 4, above referred to. The tubular member 2 forms an outer air-chamber 6 for additional air. Mounted within said air-chamber 6 is a tubular member 7 which forms a central contracted passage for the constant air supply. Within the tube 7 a nozzle or fuel-jet 8 is placed which communicates with the oil or float-chamber 3 through a horizontal tubular member 9, the latter member also supports the tube 7. Mounted in the chamber 3 is the usual float 10 connected with a lever 11 pivoted at 12 and in turn connected to a fuel-inlet-valve 13 mounted in an off-set 14 of the shell 1. Mounted below the inner tubular member 2 and communicating therewith is an air-box 15 secured to said member 2 by a stem 16. The said air-box 15 is provided with a suitable valve 17 which, when closed, diminishes the supply of air to the carbureter, thereby permitting a richer fuel or mixture to be obtained and thus promoting easy starting of the engine. The cap 4 is provided with a passage 18 for the fuel or mixture and a throttle-valve 19. A portion of the air passing through the air-box 15 enters the tube 7 and, under the influence of the partial vacuum produced by the suction created by the engine, mixes with the fuel issuing from the jet nozzle 8 thus producing the fuel or explosive mixture. When the demands of the engine require a larger amount of air than that which passes through the tube 7, additional air may be supplied from the air-chamber 6 which is controlled by an automatic valve 20 of peculiar structure and operation. This valve 20 co-operates with a seat 21 extending from the inner side of the tubular member 2 and is integral with a sleeve 22 vertically and freely movable on the inner tube 7. The lower end of said sleeve 22 has an enlargement or circumferential flange 23 which is instrumental in providing an annular recess around said sleeve which, through the effect of the air, is instrumental in maintaining the valve 20 in a balanced position. For example, when said valve is elevated so that

said valve and the flange 23 will be approximately equal distances from the seat 21, the effect of the air on the under side of said valve and on the upper side of said flange 5 will be substantially equal, thereby balancing said valve and preventing any further elevation thereof. Thus the flange 23 in connection with the weight of the valve and the effect of the air serves to prevent said 10 valve from opening too quickly, while at the same time permitting it to readily respond to the demands of the engine, admitting additional air in proportion to such demands.

15 It will be understood that when air is supplied through the auxiliary valve 20 to the mixture, an additional amount of oil is admitted through the jet-nozzle. By "mixture," it will be understood, is meant the 20 product after commingling with the constant air supplied through the tube 7. For this purpose the jet-nozzle 8 is provided with a needle-valve 25 which is suitably shaped, as is shown in Fig. 5, to furnish the 25 proper amount of oil. This valve, as illustrated in Fig. 1, is attached to a stem 26 supported in an adjusting member 27, having bearing in the cap 4. By means of the adjusting member 27, the normal relation between 30 said needle-valve 25 and the jet 8 is regulated. When the air-valve 20 is elevated through the partial vacuum produced by the suction created by the engine, the needle-valve 25 is also elevated through the 35 agency of a yoke 28 extending from the valve 20 and engaging a shoulder 29 on the stem 26 of said valve. It will be observed that the needle-valve passes through an aperture in said yoke. The arrangement is 40 such that a definite proportion of oil and air will be maintained irrespective of the volume of mixture or the demands of the engine. To prevent the mixture becoming overcharged with oil when the air-valve 20 45 initially open, the shoulder 29 is so placed as to permit of an initial free movement of said valve before the needle-valve is actuated thereby. In Fig. 3, I have shown a modified construction and arrangement in which 50 the needle-valve 31 is adjustably mounted in and is carried directly by the yoke 28. The valve, as thus shown may be adjusted by removing the cover 4. This construction also allows the passage for the mixture to be 55 in alignment with the center of the carbureter, thereby permitting the carbureter to be symmetrical in appearance and the air to pass directly therethrough with no cross or counter currents.

60 To prevent any condensation by the manifold, collecting on the valve seat 21 and the possibility of subsequent choking of the carbureter when the engine is started or accelerated, the valve seat 21 is provided with 65 an annular pocket 32 adapted to collect any

evaporation due to condensation when the carbureter is in operation.

To elevate the height of the oil level in the float-chamber and to thus promote easy starting, the pivot 12 of the float lever 11 is 70 adapted to be manually elevated. The pivot of said lever 11 is mounted in a yoke 34 pivotally secured to the lower end of an adjusting screw 35 mounted in a vertically sliding block 36. The block 36 is journaled in 75 a cap-housing 37 which forms a cover for the off-set 14. The block 36 is provided with cam-slots 38 which receive the ends 39 of a sliding member 40 mounted in the cap-housing 37. The member 40 may be actuated 80 from the front of the radiator (not shown) or from the dash by any suitable connecting means (not shown). When the sliding member 40 is drawn outwardly, the block 36 and the pivot 12 are elevated, thereby 85 raising the float level and permitting the float 10 to rise to a greater height before closing the inlet valve 13. The float level in the chamber 3 is regulated by the adjusting screw 35 while the sliding member 40 is held 90 in either of its shifted positions by pockets 41 in the cam-slots 38.

Having described my invention, I claim:

1. In a carbureter, the combination with a jet-nozzle, and a needle-valve co-operating therewith, of a tube surrounding said jet-nozzle and furnishing a constant supply of air thereto, an air valve through which additional air is supplied to the space above said jet-nozzle, the supply of air to said tube and air valve being admitted below said tube, a connection between said needle-valve and said air valve, a sleeve extended from said air valve terminating in an annular enlargement which together with said 100 air valve provides a circumferential recess around said sleeve, and a shell surrounding said air valve and sleeve and providing an air passage to said air valve, and a seat for said air valve.

2. In a carbureter, a shell providing an air-passage and a valve seat, an air-valve co-acting with said seat in providing a variable supply of air to the upper portion of said shell, a needle-valve, a tube through 115 which a constant supply of air is furnished to said needle-valve, and a yoke extending from said air valve and through which said needle-valve is guided and by which said needle-valve is subject to movement from 120 said air valve.

3. In a carbureter, the combination with a shell providing an air-passage, and a valve seat, said valve seat being constructed to provide an annular pocket on the interior 125 of the shell and around the valve seat, an air-valve co-operating with said seat to control the admission of additional air, a tube providing a constant air-passage and upon which said air valve is mounted, a needle- 130

valve surrounded by said tube, and a connection between said needle-valve and said air valve whereby the needle-valve is given a greater opening by the air valve when the latter's opening is increased.

4. In a carbureter, an inner cylinder, a jet-nozzle lying within said cylinder and surrounded by a constant air passage, an outer cylinder surrounding said inner cylinder and providing an air-chamber there-around, a variable air-supply-valve surrounding said inner cylinder and controlling the admission of air from said chamber to the space above the inner cylinder, and

10 5. a needle-valve having a shoulder controlling said jet-nozzle, said needle-valve adapted to be actuated to increase the jet opening by the movement of said variable air-supply-

valve subsequent to the initial movement of said air supply valve. 20

5. In a carbureter having a central air-passage, a tube mounted in said passage and dividing said passage into inner and outer passages, a jet mounted in said inner passage, an air-valve mounted on said tube 25 and controlling said outer passage, a fuel-valve to feed said jet actuated by said air-valve, said air-valve having an initial movement independent of the fuel-valve.

In testimony whereof I affix my signature, 30
in presence of two witnesses.

JOHN C. COLLETT.
